COMBINED CARBURETOR CHOKE AND NOZZLE

William E. Egerer, Detroit, Mich., assignor to
George M. Holley and Earl Holley

Application May 20, 1949, Serial No. 94,446

6 Claims. (Cl. 261—62)

1

The object of this invention is to improve the fuel nozzle shown in the co-pending Kittler & Winter application Serial No. 58,748 filed November 6, 1948.

The problem there is to make a choke valve serve also as the fuel nozzle of a plain tube carburetor. I have discovered that if I use an annular butterfly choke and discharge fuel into the center of the annulus from the hollow shaft on which the choke valve is mounted I will have a very satisfactory fuel nozzle and an unsatisfactory choke valve. So I then discovered that the hollow shaft which forms the stationary nozzle could carry a disc upstream of the fuel outlet which disc could just obstruct the central opening of the annular choke valve when the choke valve was closed. I would then have a still better fuel nozzle and the choke valve would be satisfactory.

Fig. 1 shows the preferred form of my invention—choke valve open.

Fig. 2 shows a cross-sectional elevation on the plane 2—2 of Fig. 1 through the choke valve when the choke valve is closed.

Fig. 3 is an exploded view showing how the choke valve is rotated.

Fig. 4 shows an alternative construction with the choke valve open.

Fig. 5 shows a cross-sectional elevation on plane 5—5 of Fig. 4 with the choke valve shut.

Fig. 6 shows a detail of the hollow stationary nozzle.

Fig. 7 shows an exploded view of the driving means for the choke valve.

Fig. 8 is a cross-sectional plan view on the plane 8—8 of Fig. 6.

In the Figure 10 is the air entrance, 12 is the choke valve located in the throat of the venturi 14. 16 is a hollow choke operating shaft which is mounted on a stationary hollow shaft 60. 17 is one of two tongues (Fig. 3) extending from the hollow shaft 16 and engaging a corresponding slot 19 in one-half of the choke valve 12. This choke valve 12 is made of two similar stampings which together form a cylinder embracing the stationary shaft 60. The two halves may be spot welded together.

An opening is provided in the center of the choke valve 12 and a disc 64, held to the shaft 60 by a cap screw 66, closes this opening when the choke valve 12 is closed as shown in Fig. 2. A radial opening 61, in the shaft 60, and a corresponding slot in the plate 64 provides an opening for fuel to discharge into the throat of the venturi 14. An inclined passage 62 connects the

hollow shaft 60 and radial opening 61 with the well 50 which is fed from a constant level fuel supply chamber 46 where the level is maintained constant at the line 47.

A restriction 48 controls the fuel/air ratio. An impact air tube 52 admits air to the well 50 through the tube 54. A low speed fuel bypass 56 is air bled at 58 to prevent a siphon action. Two outlets 42 and 44 are provided so that as the throttle 38 is first opened fuel is drawn up bypass 56 and down passage 40 in a well known manner. As the throttle continues to open fuel discharges from both outlets 42 and 44.

The throttle 38 is mounted on a shaft 39 driven by lever 41. The choke shaft 16 is driven by lever 22.

Similar numbers refer to similar parts in Figs. 4 and 1. 160 is the stationary nozzle corresponding to the nozzle 60 of Fig. 1. 112 is the choke valve. Integral with the nozzle 160 is the circular flange 164 in the middle of which is an opening 161 through which the fuel discharges. The choke valve 112, as before, is made of two similar parts embracing the nozzle 160. In order that the flange 164 can be assembled a new part 70 has been added as a bushing surrounding the hollow driving shaft 16. The left hand face of the bushing 70 is machined to conform with the shape of the venturi 14. The diameter of the bushing 70 is the same as the diameter of the flange 164. A slot 119 now extends the full distance from the outer periphery to the inner annular opening 111, otherwise it would not be possible to assemble the choke valve 112 onto the stationary nozzle 160. A shallow opening 174 is provided in the downstream face of the stationary nozzle 160 and it is located so that the concentric opening 161 is concentric with reference to the opening 174.

Operation

Assume the choke is closed as shown in Fig. 2 then the fuel is drawn up the well 50, down passages 61 and 62 into the venturi 14 where it mingles with the air which leaks around the disc 64 and choke valve 12. When the choke valve 12 is wide open the disc 64 serves to create an eddy into which the fuel is sprayed from the hollow stationary shaft 60.

The fuel is thus spread in a fan over the annular choke valve which serves to distribute the fuel uniformly in the air stream.

The operation of the carburetor shown in Figs. 4, 5, 6, 7, and 8 is substantially identical with that shown in Figs. 1, 2 and 3 with this exception:

The nozzle 161 is now concentric with reference to the venturi 14 whereas before it was necessarily located eccentric in order to clear the cap screw 66.

What I claim is:

1. A carburetor having a Venturi mixing chamber, a mixture outlet and a throttle valve therein, a first hollow shaft mounted in a fixed position transversely in the throat of said venturi, a second hollow shaft concentrically mounted on said first shaft, a butterfly choke valve having two radial cylindrical portions rotatably mounted on the first shaft, driving means on said second shaft, corresponding driven means on said choke valve, a constant level fuel supply chamber connected to the center passage of said first shaft, a radial opening in the first hollow shaft discharging downstream into the venturi, an opening in the center of said butterfly choke valve so that the fuel is discharged into the center of the venturi in all positions of the choke valve.

2. A device as set forth in claim 1 in which there is a disc mounted on the stationary shaft in a horizontal position so as to intercept the opening through the first hollow shaft and so located as to close the air opening in the center of said choke valve when the choke valve is closed without obstructing the flow of fuel.

3. A choke valve and fuel nozzle construction comprising an air passage, a fuel nozzle projecting at right angles into the air stream, an annular butterfly choke valve rotatably mounted on the nozzle said nozzle terminating in an opening in the middle of the air stream facing downstream, and a stationary disc mounted on the nozzle immediately upstream of the fuel outlet from said nozzle.

4. A choke and fuel nozzle construction comprising a Venturi mixing passage, a fuel nozzle projecting at right angles to the air stream into the throat of said venturi, a two part flat annular choke valve embracing said nozzle so as to rotate thereon, a radial opening in said nozzle discharg-

ing downstream inside the annular opening in said choke valve equally distributed on the upper inside edge of the downstream half of said valve, a disc carried by said nozzle upstream of said discharge point so as to fit into the opening of the annulus when the choke valve is closed.

5. A choke and nozzle construction comprising a Venturi mixing passage, a stationary fuel nozzle projecting at right angles to the air stream into the throat of said venturi, a flat annular choke having a tubular radial portion adapted to fit over the nozzle, a hollow shaft mounted on an extension of the nozzle clear of the venturi and engaging with said annular choke valve, a radial opening from said nozzle pointing downstream and located within the central opening of a disc carried by said nozzle immediately upstream of said opening.

6. A carburetor having an air entrance including an annular butterfly choke valve with radial bearings, a one piece fuel nozzle discharging downstream into the center of the air stream and located at right angles thereto and having a disc normal to and in the center of the air flow made integral with the nozzle, said disc being located adjacent to and upstream of the point of discharge of said nozzle, said nozzle being made to act as the pivot for the bearings of the butterfly choke valve, the central opening of said annular choke valve being equal in diameter to the diameter of the said disc, and a mixture outlet and a throttle valve therein.
